UNITED STATES PATENT OFFICE.

ORA O. HAYES, OF MINNEAPOLIS, MINNESOTA.

ROOF-PEAK.

1,347,541.

Specification of Letters Patent. Patented July 27, 1920.

Application filed March 2, 1920. Serial No. 362,864.

To all whom it may concern:

Be it known that I, ORA O. HAYES, a citizen of the United States, residing at Minneapolis, in the county of Hennepin and State of Minnesota, have invented certain new and useful Improvements in Roof-Peaks, of which the following is a specification.

My invention relates to peaks for roofs, and the object is to provide a weatherproof hood and securing means at the apex of conical and pyramidal shaped roofs such as are used particularly on cylindrical silos. Further objects will be disclosed in the course of the specification. The invention is clearly illustrated in the accompanying drawing, in which:

Figure 1 is a top view of the middle portion of a conical roof equipped with my improved hood.

Fig. 2 is a diametrical section as seen substantially on the line 2—2 in Fig. 1.

Referring to the drawing by reference numerals, 3 designates the radial wedge shaped boards with which it is common to construct inclined circular roofs. On the peak of the roof I provide a tight fitting hood 4 on the top of which is a block 5 through which and through the center of the hood and roof extends a bolt 6 having

a nut 7 at its lower end. Between the nut 30 and the underside of the roof is clamped a circular block 8. A conical cap 9 covers the block 5 and bolt 6 and is tightly secured by means of rivets 10 or other suitable means to the hood 4.

The construction, use and advantages of the device are obvious. With the parts in their proper positions and with the nut 7 screwed up tightly, as shown, the peak of the roof is not only made water-tight, but 40 the device also provides simple and easily applied means whereby all the radial boards of the roof may be secured and held in firm and rigid position.

Having now fully shown and described 45 my invention, what I claim to be new and desire to protect by Letters Patent is:

In combination with a conical roof, a hood adapted to cover the apex thereof, a block positioned over the apex of said hood, 50 a bolt extending through said block, hood and roof, and means at the lower end thereof for clamping said roof and hood together, a conical cap adapted to cover said block and have its edge tightly secured to said 55 hood.

In testimony whereof I affix my signature.
ORA O. HAYES.
